UNITED STATES PATENT OFFICE.

ALBERT A. KNISELEY, OF DETROIT, MICHIGAN.

GAS HEATER.

Application filed April 17, 1924. Serial No. 707,134.

To all whom it may concern:

Be it known that I, ALBERT A. KNISELEY, a citizen of the United States, and residing at Detroit, in the county of Wayne and 55
5 State of Michigan, have invented a new and Improved Gas Heater, of which the following is a specification.

This invention relates to gas heaters especially adapted to be used for heating garage 10 structures and it consists in the novel features hereinafter described and claimed.

An object of the invention is to provide a heater which uses gas as a fuel with means for leading a current of air from the exterior to the interior of a garage structure, the parts and features being so arranged that the said current of air may absorb the heat units as it passes through the heater and consequently is discharged into the 20 garage structure in a heated condition.

With the above objects in view the heater comprises a housing which passes through the wall of the garage structure, a door being hingedly mounted in the housing at its 25 upper edge and at a point between the ends of the housing. A gas burner is located in the inner portion of the housing and an air conduit is located above the burner and is adapted to receive a current of air under 30 the lower edge of the door and from the outer portion of the housing and deliver the same through the top of the housing into the garage structure.

These objects and the several novel features of the invention are hereinafter more fully described and claimed and the preferred form of construction by which these objects are attained is shown in the accompanying drawings in which—

40 Fig. 1 is a fragmentary section view of a garage wall with the heater applied and shown in section.

Fig. 2 is a plan view of the heater.

Fig. 3 is an end elevation of the heater.

45 Fig. 4 is a fragmentary sectional view of the roof of the garage showing a fume pipe passing therethrough.

As illustrated in the accompanying drawings the wall of a garage structure is indicated at 1 and the roof thereof at 2. A 50 housing 3 passes transversely through the

wall 1 and its major portion is disposed interiorly of the garage structure. A gas burner 4 is located in the lower inner portion of the housing 3. A valve controlled 55 gas pipe 5 is adapted to lead the gas to the burner 4 in the usual manner. A pilot burner 6 is also located in the lower inner portion of the housing 3 adjacent the burner 4 and is adapted to receive gas from the 60 pipe 5 in the usual manner. The pilot burner 6 may be maintained in a lighted condition all of the time and may light the gas at the burner 4 when the valve in the pipe 5 is opened and permits the gas to flow 65 to the burner 4 in the usual manner. A fume pipe 7 connects with a cone shaped hood 16 hereinafter referred to. The said pipe 7 passes through the roof 2 as best shown in Fig. 4 of the drawings. A ventilating sleeve 8 is mounted upon the upper portion of the pipe 7 and also passes through the roof 2. A flashing 9 is connected with the ventilating sleeve 8 and the roof 2 in the usual manner and as shown in Fig. 70 75 4 of the drawings.

A door 10 is hingedly mounted at its upper edge in the upper intermediate portion of the housing 3 and is disposed transversely thereof. The door 10 is flanged outwardly at the lower edge at 12 as shown and a partition 11 is provided across the housing 3 having raised beads 30 and 31 which space the door 10 from the panel 11, the door resting on these beads 30 and 31 80 and providing an air space between the door 10 and panel 11 to prevent the door from becoming heated. The panel 11 is provided at the lower edge with an inwardly disposed flange 13 and a handle 14 is 85 secured to the lower portion of the door 10.

An air conduit 15 is located in the inner portion of the housing 3 and is disposed vertically above the burners 4 and 6. The inlet end of the conduit 15 is disposed below the lower edges of the flanges 12 and 13 of the door 10 and panel 11 and the delivery end of the conduit 15 passes through the side of a cone shaped hood 16 mounted upon the top of the housing 3 and which is 95 located vertically above the said burners. The pipe 7 is connected with the hood 16 100

as best shown in Fig. 1 of the drawings. A screen 17 (see Fig. 2) is disposed across the outlet end of the conduit 15 and prevents rags or other material from being 5 thrown or deposited in the conduit 15. The cone shaped plate 16 prevents the setting of oil cans or similar receptacles upon the top of the housing 3 above the burners 4 and 6. The flange 13 of the inner panel 10 11 is recessed at 18 to receive the lower portion of the conduit 15 as shown in Fig. 1 of the drawings. The conduit 15, as will be understood from Fig. 1, is made up of a series of pipe sections 19, 19^b, 19^c, 19^d and 15 chambers 20. The lowermost conduit 19 is in the form of an elbow having an inlet end 19^a and opening at its upper end to the lower chamber 20. The next pipe section 19^b connects with the first chamber and dis- 20 charges to the second chamber. The third section 19^c connects at one end with the second chamber and the other end with the third chamber and the last pipe section 19^d discharges through the hood 16 and is pro- 25 vided with a screened outlet opening 17 as heretofore stated. The pipe sections are arranged in staggered relation as shown—that is, the end of one pipe section connects with one side of the chamber and the next pipe 30 section connects with the opposite side of the same. Preferably the chambers are successively of less volumetric content successively decreasing in diameter. Baffle plates 21 are mounted upon the inner surface of 35 the inner panel 11 and are adapted to bear against the edges of the chambers 20 whereby the fumes and heated gases from the burners 4 and 6 are directed away from the door 10 and toward the intermediate por- 40 tions of the disks 20.

It is apparent that when the burners 4 and 6 are lighted the heated gases and fumes come in contact with the exterior surfaces of the pipes 19 and chambers 20 and the 45 heat units are absorbed by the said pipes and chambers and transmitted to the current of air which is passing therethrough. The various parts of the conduit 15 are preferably welded together to prevent a 50 leakage of the gases into the conduit.

From the foregoing description it becomes evident that the device is very simple and efficient in operation, will not easily get out of order, provides a safe means for heating a garage or similar structure and provides a device which accomplishes the 55 objects described.

Having thus fully described my invention, its utility and mode of operation, what I 60 claim and desire to secure by Letters Patent of the United States is—

1. A heater for a building comprising a housing opening through a wall of the building to atmosphere, a heater at the inner end 65 of the housing, a door extending across the

housing and shielding the heater from external atmosphere, said door adapted to be opened to expose the heater to atmosphere and when closed being spaced from the bottom wall of the housing providing for an 70 ingress of air to the heater, said heater including a burner and a series of chambers and pipe sections connecting the same providing a conduit, the conduit opening to atmosphere below the door edge and discharging to the space to be heated, and an exhaust conduit for the gases of combustion leading to the exterior of the building. 75

2. A heater for a building comprising a housing opening through a wall of the 80 building to atmosphere, a heater at the inner end of the housing, a swinging door extending across the housing and in conjunction with the wall of the housing about the heater enclosing the heater, provision being made for an ingress of air through the housing to the heater for combustion purposes, said heater comprising a burner and a series of vertically spaced air chambers thereabove, and pipe sections connecting the chambers, the first pipe section opening toward the open side of the housing to receive air and the pipe section for the last of the chambers discharging to the 85 space to be heated, the said chambers successively decreasing in size from the lower to the upper chamber, and a flue for the 90 gases of combustion. 95

3. A heater comprising a housing, a door hingedly mounted at its upper edge in the upper portion of the housing and at a point between the ends thereof and having its lower free edge spaced from the bottom wall of the housing, a burner located in the lower portion of the housing behind the door and a conduit located in the housing above the burner and having an inlet end disposed below the lower edge of the door and an outlet at the upper portion of the housing, said conduit being disposed above the 100 burner. 105

4. A heater comprising a housing, a door composed of spaced panels providing an air space therebetween, said door being hingedly connected at its upper edge to the upper intermediate portion of the housing and disposed transversely across the housing, the lower edge of the door being spaced from the bottom wall of the housing, a heater located in the inner portion of the housing behind the door, and a conduit located in the inner portion of the housing behind the door and disposed above the heater and having its inlet end disposed below the lower edge of the door. 115 120

5. A heater comprising a housing, a door hingedly mounted at its upper edge in the intermediate portion of the housing and disposed transversely thereof, a heater located 125 in the lower inner portion of the housing 130

behind the door, a conduit located in the housing above the heater and having its inlet end disposed below the lower free edge of the door, said conduit being composed of a series of pipe sections with intervening chambers disposed between the pipe sections, said pipe sections being connected at their adjacent ends to the opposite sides of the chambers, said chambers being disposed above the heater and the door being inclined 10 against the side edges of the chambers.

In testimony whereof I sign this specification.

ALBERT A. KNISELEY.
